CLAIM

An ornamental design for a motorcycle carrier, as shown and described.

DESCRIPTION

Cross-reference to related applications

U.S. Application Ser. No. 29/545,863

U.S. Application Ser. No. 08/055,551

U.S. Application Ser. No. 09/994,345

U.S. Application Ser. No. 09/372,374

U.S. Application Ser. No. 11/888,261

U.S. Application Ser. No. 29/273,943

U.S. Application Ser. No. 29/234,564

U.S. Application Ser. No. 29/318,742

FIG. 1 is a front perspective view of the motorcycle carrier.

FIG. 2 is a front elevation view of the motorcycle carrier.

FIG. 3 is a rear elevation view of the motorcycle carrier.

FIG. 4 is a top plan view of the motorcycle carrier.

FIG. 5 is a bottom plan view of motorcycle carrier.

FIG. 6 is a left side elevation view of the motorcycle carrier; and,

FIG. 7 is a right side elevation view of the motorcycle carrier.
